American Can Company, New York, N.Y., a corporation of New Jersey

Filed Aug. 18, 1960, Ser. No. 61,804

Term of patent 14 years

(Cl. D83—12)

Fig. 1

The fragmentary broken-line representation of a container is for illustrative purposes only.

I claim:

The ornamental design for spoon attachment for a dispensing container, substantially as shown and described.
